UNITED STATES PATENT OFFICE.

ALBERT THOMAS LOCHNER, OF CHICAGO, ILLINOIS, ASSIGNOR TO WODACK ELECTRIC TOOL CORPORATION, OF CHICAGO, ILLINOIS, A CORPORATION OF ILLINOIS.

POWER-HAMMER.

1,356,297.

Specification of Letters Patent. Patented Oct. 19, 1920.

Application filed December 26, 1918. Serial No. 268,305.

To all whom it may concern:

Be it known that I, ALBERT THOMAS LOCHNER, a citizen of the United States, residing at Chicago, in the county of Cook and State of Illinois, have invented certain new and useful Improvements in Power-Hammers, of which the following is a specification.

The invention relates to power hammers and has for one of its objects the provision of a hammer of a very practical character wherein the relative arrangement of the parts is such as to make the tool convenient in operation.

15 A further object of the invention is to provide spring means advantageously arranged relative to the plunger-actuating mechanism for cushioning the plunger when the tool is not applied to the work.

20 The objects of the invention thus generally stated, together with other and ancillary advantages, are attained by the construction and arrangement illustrated in the accompanying drawings forming part 25 hereof, in which Figure 1 is a fragmentary elevation-section of a power hammer embodying the features of my invention. Fig. 2 is a transverse section on line 2—2 of Fig. 1. Fig. 3 is a fragmentary longitudinal sectional view showing details of construction.

The hammer comprises, in general, a body 1, a plunger 2, reciprocable in the body by actuating mechanism 3, and a motor 4 for driving the plunger-actuating mechanism. The body 1 comprises a tubular member 5 within which the plunger 2 is slidable and which is threaded onto the forward end of a tubular extension 6 of a substantially cylindrical casing 7 which encloses the actuating mechanism 3. Said tubular member 5 and extension 6 form the hammer barrel.

45 The motor 4 is mounted in a suitable way within the casing 7 which is preferably made up of separate sections, consisting, for example, of a forward section 7^a and a rear section 7^b secured together by means of bolts 8 with an intermediate section 9 entered therebetween to accommodate parts of the operating mechanism to be later described. Herein a plate 10 is shown as forming a bearing for the forward end of the motor spindle 11, 55 the rear section 7^b, of the casing, and ring

9 being provided at their adjacent edges with an interior annular groove to receive the peripheral edges of the plate 10 and thereby hold it in position. At the forward end of the body a tool holding sleeve 12 is 60 secured within the tubular member 5, and at its rear end the body has a handle 13 suitably secured to the rear casing section 7^b.

The plunger 2 is mounted on the forward 65 end of a rod 14 slidable in a bearing block 15 fixed in the tubular extension 6; and on the rear end of said rod is fixed a head 16. A cam disk 17, located between said head and the forward end of the casing 7, is 70 operatively connected with the motor for rotation thereby and is provided with one or more cam surfaces 17^a with which an arm 16^a on the head (Fig. 2) is arranged to slidably engage. It will be seen that as 75 the cam disk is rotated, the cam surfaces 17^a coöperate with the arm 16^a to move the plunger 2 rearwardly. This movement takes place against the action of a coiled spring 18 surrounding the rod 14 and bearing 80 between the plunger 2 and the bearing block 15, and it will be apparent that when the arm 16^a rides off from a cam surface 17^a the spring 18 will impel the plunger forwardly to strike a blow upon the shank of 85 a tool a.

Preferably the plunger rod 14 is made square, as shown, the opening through the bearing block 15 being similarly shaped in order that the rod will be effectively held 90 against rotation. The disk 17 is provided with a central opening 19 somewhat larger than the thickness of the rod so as to enable the rear end thereof to pass freely through the opening. In order to provide an efficient mounting for the cam disk, independent of the rod 14, I have provided a tubular bearing stem 20 thereon which extends forwardly into a bore or socket 15^a in the forward end of the bearing block 15, and preferably a ball thrust bearing 21 is interposed between the disk and the bearing block.

The means by which the cam disk is operatively connected to the motor for rotation thereby comprises a spur pinion 22 fixed 105 on the forward end of the motor spindle 11 and meshing with a spur gear 23 fixed on the rear end of a tubular stem 24. Said stem is mounted on a shaft 25, the opposite ends of which may be suitably mounted in 110

the forward wall of the casing 7 and in the bearing plate 10, respectively, and the forward end of the stem is provided with gear teeth 24^a so as to mesh with gear teeth 26 5 provided on the periphery of the cam disk. It will be observed that the arrangement of the gearing connections as a whole is such that the hammer barrel may be offset toward the periphery of the casing 7, which 10 renders the hammer readily adaptable to use in corners and similarly restricted places, thus increasing the convenience of the hammer in operation.

When the motor is operated a rapid reciprocation of the plunger 2 is effected by 15 means of the actuating mechanism operatively connected with the motor in the manner just described, and the plunger in such reciprocation is adapted to act upon the 20 shank of the tool *a* when the latter is applied to the work. When, however, the tool *a* is not applied to the work and the plunger is running idly, the impact of the blow is received by a coiled spring 27 (Fig. 3) so that 25 the wear and tear upon the parts which would otherwise result is substantially eliminated. I have arranged said spring 27 in such a manner as not to require any more space than is necessary for other parts and 30 so as not to interfere in any way with the efficient operation of the tool. To this end the cam disk is provided in its rear face with a socket 28, and the spring 27 is entered in said socket around the rod 14 in front of the 35 head 16. The spring, it will be understood, is made of such length that it will affect the operation of the plunger only when the tool is not applied to the work.

For the purpose of minimizing friction 40 between the cam disk and the arm 16^a, a roller 29 may, if desired, be mounted in the arm.

I claim as my invention:

1. A power hammer having, in combination, a plunger, spring means tending to

move the plunger in one direction, means for moving the plunger in the opposite direction including a rotatable cam disk and a head adapted to coöperate therewith, a rod having said plunger fixed on one end and said head fixed on the other end, and a coiled cushioning spring between said disk and head and surrounding the rod, said disk having a socket in its face adjacent the head for receiving said spring. 50

2. A power hammer having, in combination, a body, a plunger, an operating member for the plunger, a rotatable cam member having a tubular stem journaled in the body coaxially of the plunger, said operating member being adapted to operatively engage with said cam member to be moved thereby in one direction, a spring tending to move the plunger in the opposite direction, and a cushioning spring interposed between 60 said operating member and said cam member. 65

3. A power hammer having, in combination, a body, a plunger, a rod having said plunger fixed on one end, a bearing member through which said rod is slid able, a rotatable cam member having a tubular stem journaled in said bearing member, said rod extending through said cam member and its 70 stem and having a head thereon adapted to coöperate with the cam member to move the plunger in one direction, and spring means 75 tending to move the plunger in the opposite direction.

4. In a power hammer having a plunger, 80 mechanism for imparting movement to the plunger including a rotatable cam member and a non-rotatable member operatively associated therewith to impart movement to the plunger, and a spring interposed between 85 said members.

In testimony whereof, I have hereunto set my hand.

ALBERT THOMAS LOCHNER.
